SPRING ARCH SUPPORT FOR SHOES

James E. Ludlam, Westbrook, Conn.

Application July 24, 1948, Serial No. 40,565

9 Claims. (Cl. 36—71)

1

My invention relates broadly to shoes and more particularly to an improved construction of arch supports for shoes.

One of the objects of my invention is to provide an improved arch support including a semi-rigid support and slideable coacting spring supporting members associated therewith with means for supporting the slideable spring members intermediate the ends thereof.

Still another object of my invention is to provide an improved arch support including a semi-rigid supporting member with yieldable spring supports carried thereby and a transverse yieldable support carried by the semi-rigid support and operating to support the yieldable spring supports.

A further object of my invention is to provide an improved arch support including a semi-rigid supporting member which supports substantially longitudinally extending slideable and yieldable members in combination with a lateral supporting member carried by the semi-rigid support and forming a support for the yieldable members intermediate the ends thereof.

Still another object of my invention is to provide an improved arch support proportioned to provide substantial support for the various arches of the foot including a substantially longitudinally extending yieldable arch with a laterally disposed supporting member carried by the arch and serving as a resilient reinforcement for the yieldable arch intermediate the ends thereof.

A still further object of my invention is to provide an arrangement of metatarsal supporting member for use in combination with a yieldable arch.

Another object of my invention is to provide an improved construction of metatarsal support for installation in shoes.

Other and further objects of my invention reside in the improved construction and combination of a longitudinal spring arch support with a laterally coacting spring support therefor as set forth more fully in the specification herein-after following by reference to the accompanying drawings in which:

Figure 1 is a schematic plan view of the skeletonized bones of the foot and illustrating in plan view the association of the improved arch of my invention therewith; Fig. 2 is a side elevational view showing one manner of installing the improved arch of my invention in a shoe for providing support for the arch of the foot wherein I have illustrated the skeletonized arrangement of the bones of the foot; Fig. 3 is a plan view of

2

the improved arch of my invention looking at the bottom thereof; Fig. 4 is a view similar to the plan view of Fig. 3, but looking at the top of the arch; Fig. 5 is a longitudinal sectional view taken substantially on line 5—5 of Fig. 4; Fig. 6 is a transverse sectional view taken substantially on line 6—6 of Fig. 4; Fig. 7 is a transverse sectional view taken substantially on line 7—7 of Fig. 4; Fig. 8 is a transverse sectional view taken substantially on line 8—8 of Fig. 4; Fig. 9 illustrates the application of the principle of my invention to an arch support for use in women's shoes; Fig. 10 is a schematic view illustrating the manner of mounting the arch support in a welt-type shoe; Fig. 11 is a transverse sectional view taken substantially on line 11—11 of Fig. 10; Fig. 12 is a transverse sectional view taken substantially on line 12—12 of Fig. 10; Fig. 13 is a transverse sectional view taken substantially on line 13—13 of Fig. 10; Fig. 14 is a plan view illustrating a modified form of the arch of my invention installed in a relatively narrow shoe in which a sewing operation may be performed relatively close to the longitudinal springs of the arch; Fig. 15 is a plan view of the arch of Fig. 14 wholly removed from the shoe; Fig. 16 is a transverse sectional view on line 16—16 of Fig. 15; Fig. 17 is a plan view of the blank used in the form of arch shown in Figs. 14, 15 and 16, with the springs removed, but showing the fastening holes by which the springs may be attached for both narrow and wide width shoes and in which the arch is shaped for installation in different types of shoes such as vulcanized rubber sole shoes or regular leather shoes; Fig. 18 is a plan view of a further modified form of arch embodying my invention in which the reinforcing means for the semi-rigid portion of the arch extends into close proximity to the mounting means for the longitudinally extending springs of the arch; Fig. 19 shows a further modified form of arch embodying my invention with a metatarsal supporting member added thereto; Fig. 20 is a transverse sectional view taken substantially on line 20—20 of Fig. 19; Fig. 21 is a transverse sectional view taken substantially on line 21—21 of Fig. 19; Fig. 22 is a longitudinal sectional view taken substantially on line 22—22 of Fig. 19; Fig. 23 is a longitudinal sectional view taken substantially on line 23—23 of Fig. 19; Fig. 24 is a top plan view of the metatarsal supporting member which is added to the arch support of my invention; Fig. 25 is a bottom plan view of the metatarsal supporting member of Fig. 24; Fig. 26 is a side elevational view of the metatarsal supporting member il-

lustrated in Figs. 24 and 25; Fig. 27 is a longitudinal sectional view taken substantially on line 27—27 of Fig. 24; Fig. 28 is an end view of the metatarsal supporting member illustrated in Figs. 24—27; Fig. 29 is a transverse sectional view taken through the metatarsal supporting member substantially on line 29—29 of Fig. 24; Fig. 30 shows a further modified form of arch support embodying my invention in which the longitudinal springs are secured at their rearward ends and left free to move at their forward ends; and, Fig. 31 is a longitudinal sectional view taken substantially on line 31—31 of Fig. 30.

My invention is directed to an arch support constructed to support the various arches of the foot from heel to ball, the inner longitudinal arch, the outer longitudinal arch, the transverse arch and the metatarsal arch. The improved arch support is for use in the construction of welt shoes, but may be used in the construction of all types of shoes. It may also be made in the form of a separate arch support to be inserted inside of a shoe. The outer longitudinal portion of the arch support of my invention will support the bones of the foot within the outer longitudinal arch area of the foot, and the forepart of the arch support extends laterally at its forward portion inward toward and ending under the first metatarsal bone of the foot, supporting all of the metatarsal bones. The arch support is semi-rigid and is preferably, but not necessarily, made of lightweight spring steel, and is intended to have a slight springing action under pressure of body weight. The arch support contains a sunken or downstruck rib extending from the heel portion throughout its almost entire length for reinforcing the support; or the said reinforcing rib may be discontinued at its partially forward end. The inner portion of the arch support is cut away to allow ample space for the mounting of a spring or a pair of coacting springs. The arch support may be made in various widths, according to the type of shoe into which it is incorporated, and as light in weight as possible, the object being to add as little weight as possible to the finished shoe. The springs or spring extend from the heel portion to the forward lateral arm portion under the inner longitudinal arch of the foot, with a slot at either end of said springs or spring. There is a hole drilled at either end of the outer body at the inner side through which there are rivets which extend through the slots of said springs or spring and provide connecting means between the semi-rigid support and the springs. This method of construction allows free and complete yieldability through slidable action of said springs or spring when the body weight is brought to bear on them. In the use of two springs, one is superimposed above the other which will act as a single unit, bringing perfect coordination in action. This construction is extremely beneficial to the arch muscles of the foot and to the complete springing action. By making the springs or spring with a slot at either end which will slide and yield downward freely in conjunction with rivets, and raised and shaped to meet every contour of the shape of the inner longitudinal arch of the foot, and placed, as far as possible within the insole of a shoe, toward the inner longitudinal portion of the foot, the arch serves to support a wider portion of the arch of the foot. As an alternative form the springs may be fixed at one end and arranged to slide at the other end.

The inner soles and outer soles of many shoes are constructed quite narrow between the heel

and ball, known as the shank portion of a shoe. This is particularly true in women's shoes. The inner longitudinal arch of the foot thus depends on the thin leather or cloth upper of the shoe almost entirely for support and with continuous walking on hard surfaces eventually lead to arch weakness, particularly in high heeled shoes. Therefore, I provide widened inner and outer soles at the shank or arch portion of shoes. This method of improved design not only will give greater support to the foot but in addition requires an arch support to raise and hold the inner shank portion of the shoe up to the foot which will prevent foot weakness during the life of the shoe. This widening of the inner and outer soles is accomplished with carefully designed patterns, the width being added principally at the inner side to support, that is, the inner longitudinal arched portion of the foot. Therefore with this form of construction including the innersole and the inner longitudinal spring portion of the arch support of my invention, I provide for the foot a greatly improved arch support by supporting the raised inner portion or inner longitudinal arch of the foot through slidable springing action. Furthermore, by making the springs or spring slotted at either end, I make allowance for an immediate and easy downward movement when the body weight is brought to bear on the foot with each step.

The inner longitudinal springs or spring of my arch support are highly tempered to give continued springing action and must be thin in order to give best results. Some breakage may occur through overtempering of the springs or spring, which past experience has proven must be anticipated. Therefore, in order to prevent such a condition, I place another lateral spring which is riveted with one or more rivets to the outer portion of the semi-rigid arch support at a position best suited to prevent breakage of the main inner longitudinal springs or spring, and placed primarily at the astragalo-scaphoid-cuneiform weight-bearing portion of my support. The said lateral spring extends inwardly under the main inner longitudinal springs or spring. This arrangement is believed to be unique, giving added support to the transverse arch of the foot and is very helpful in the prevention of breakage within the delicate structure of the arch support of my invention.

In the natural manner of walking, the heel first strikes the ground, has a tendency to roll inward, bringing the inner longitudinal arch of the foot downward with great pressure and ending with the foot rolling forward toward the toes, thus ending each step. In explanation of foot action, it is evident that as the heel first strikes the ground and pressure moves forward in the various parts of the foot, the next portion of the foot to receive pressure is the astragalo-scaphoid-cuneiform portion. Most shoes support the foot under the outer longitudinal arch portion, but have a tendency to lower and lose their effectiveness of support after a period of time with continued wear unless a wider arch support is applied under the innersole when constructed to act as a continual support throughout the entire life of the shoe. It is here that I have designed my arch support wide enough to overcome any change in support during the life of the shoe, yet light enough in weight to yield slightly under body weight.

Knowing that the foot has a tendency to roll inward somewhat with each step, bringing a

downward pressure all along the inner longitudinal high-arched portion of the inner longitudinal arch of the foot, and in order to support this portion of the foot flexibly with perfect timing and coordination, I place two springs, one above the other, directly under this portion of the foot. With slots at either end of said springs or spring, the rear slot slides instantly as pressure is first brought to bear at this point. As the body weight pressure carries forward along the springs, complete pressure is absorbed by the yielding of the springs or spring wherein the slide slot at the forward end carries off the completed action in movement. The lateral spring arm at the forepart of the outer longitudinal portion of my arch support gives support to the five metatarsal bones of the foot, a permanent support during the entire life of the shoe. The high point of support under the inner longitudinal arch of the foot is at the astragaloscapoid portion, which demands that the shaping of the springs or spring may be perfectly shaped to the foot at this portion by having them extend full length, and reinforced by the lateral or transverse spring. This construction will give extraordinary comfort to the wearer and complete assurance of non-breakage during the entire life of the support.

In a standing barefoot position the outer longitudinal arch portion of the foot is the lower weight-bearing portion. The inner longitudinal arch is much more muscular, however, and being highly arched does not touch the ground and naturally yields downwardly when the weight of the body is brought to bear on this arch. The bones of the foot are practically of a ball and socket formation, which construction allows for only a very slight yieldability within the tarsus portion of the foot, including the metatarsal bones. Supporting these bones, with slight yieldable action, are ligaments and also muscles which yield freely, proving conclusively that a spring support is necessary to the well being and general comfort of the foot, particularly a normal foot. The bones comprising the high portion of the foot above the muscles of the inner longitudinal arch are the astragalus, scaphoid and cuneiform bones. The continual downward thrust of weight with each step at this particular portion of the arch, demands that the high curvature of the springs or spring of my support shall be at this portion of said springs. I have found a more perfect shaping of the springs or spring can be accomplished by having said springs or spring to extend full length bridging the cutaway portion and allowing same to rest on top of the outer supporting portion together with the extra lateral extension spring attached to the outer portion of my arch support, giving a safe and added support at approximately the astragalus-scapoid portion of the foot. I believe the design of my arch support, when incorporated within the arch portion of a shoe between the heel and ball functions perfectly with the natural spring action of the human foot, allowing a slight spring action under the outer longitudinal arch, a complete spring action under the high arched inner longitudinal arch and with added lateral spring action under the transverse arch.

Another desirable feature of my arch support is that by placing the longitudinally extending springs or spring at the inner side of the foot and the outer supporting portion at the outer side of the foot, with the cutaway portion and the extra lateral spring associated with the longi-

tudinally extending springs instead of placing the spring portion directly above a firm lower portion, my arch support can be made thin to acquire a perfect fit to the innersole of the shoe with no raised portion showing after the outer sole is stitched and attached. It can be readily incorporated during manufacture of a shoe by not having so much depth in the shank, and therefore far more comfortable in the wearing of the finished shoe, and also by widening my support it will support a greater area of the width of the arch of the foot. It is also very acceptable to the manufacturer and economical in production, thereby adding very little extra cost to the finished shoe. When made in the construction of a shoe requiring special support, or when made as a separate arch support to be inserted into a shoe, my support may be made of heavier and stronger materials and also in various shapes and contours. This support is of great benefit also in the making of shoes of orthopedic design by springing the foot which automatically helps in restoring weakened muscles.

Where narrow insole patterns are employed according to the principles of my invention the longitudinally extending springs are supported closer to the main body of the semi-rigid support.

The shape of the heel portion of my support may be varied in order to give the best results in attaching the support to the various types of heels used in the manufacture of all types of shoes. I may shape the forepart of my support longer at the forward end at the inner side under the first mentioned bone and graduate same to a shorter portion at the outer side, or it may be equalized at the forepart, according to the width of support used and the width of shoes into which same is incorporated.

I may also make the springs or spring curved in shape under the inner longitudinal arch to more readily follow the curved line of the innersole and outersole of shoes, particularly in women's shoes where lesser space in narrow widths is available.

I also provide a metatarsal support which is readily attachable to the frame structure of the spring arch of my invention. The metatarsal support is formed from metal or plastic or rubber or leather or any desired material and shaped to provide adequate support for the ball of the foot.

Referring to the drawings in detail, reference character 1 designates a shoe which encloses the foot, which is shown in a skeletonized view as embodying the calcaneus 2, the astragalus 3, the tibia 4, the scaphoid 5, the internal cuneiform 6, the metatarsal 7, and the phalanx bones 8. The various tendons and muscles which must be supported by the arch support of my invention have not been shown. The insole of the shoe 1 is designated at 9 in superimposed relation with respect to the outersole 10.

The arch support is shown at 11 and in the arrangement illustrated in Figs. 1, 2, and 10-14. The arch support is built in as an integral part of the shoe. It will be understood, however, that the arch support of my invention may be readily applied as an insert in the shoe. The arch support 11 is stamped from sheet metal and comprises a longitudinally extending plate portion 12 which is strengthened by a downstruck longitudinally extending rib 14. The longitudinally extending plate portion 12 is enlarged at the side thereof at opposite ends of the plate, terminating in a metatarsal supporting portion 15 and a calcaneus supporting portion 16. The metatarsal

supporting portion 15 extends forwardly in an angular direction away from the longitudinally extending plate portion 12 beyond the longitudinal axis of the arch support in an unsymmetrical form, while the calcaneus supporting portion 16 is symmetrically formed with respect to the longitudinal axis of the arch support. The metatarsal supporting portion 15 and the calcaneus supporting portion 16 are both connected through curved connecting portions with the longitudinally extending plate portion 12.

Thus, an arch support is provided having a longitudinally extending plate portion 12 at one side with an unsymmetrical metatarsal supporting portion 15 projecting from the side of one end thereof and a calcaneus supporting portion 16 of symmetrical contour extending from the side of the other end thereof. Two spaced supporting areas are thus provided at 15a and 16a, and across those supporting areas I arrange a longitudinally extending spring device represented generally at 17. The longitudinally extending spring device 17 in the form of my invention illustrated in Figs. 1-7 comprises a pair of coacting resilient spring strips 18 and 19 arranged in superimposed relation and each provided with aligned longitudinally extending slots at opposite ends thereof.

In the form of my invention illustrated in Figs. 1-8, strip 18 is slotted at 18a and 18b, while strip 19 is slotted at 19a and 19b. Rivet members 20 and 21 extend through the supporting area 15a and 16a, respectively, and through the aligned slots 18a-19a and 18b-19b, respectively, and are headed over to secure the rivets solid to the arch support and in such relation to the strip members 18 and 19 as will allow the strip members 18 and 19 to slide at opposite ends thereof simultaneously with a yielding movement in a vertical direction which is permitted by the flexible assembly which I have shown. The spring strips 18 and 19 are disposed on an angle with respect to the longitudinal axis of the arch support, the angle diverging from a center substantially beyond the calcaneus supporting portion 16.

In a position intermediate the enlarged ends of the plate member 12 which constitute the metatarsal supporting portion 15 and the calcaneus supporting portion 16, I mount a transversely extending spring strip 22 on the plate portion 12. I select the point of support for the transversely extending spring strip 22 at 23 on the longitudinally extending plate portion 12 intermediate the metatarsal supporting portion 15 and the calcaneus supporting portion 16. The proper positioning of spring strip 22 in the structure of my invention is highly important, and as represented in Fig. 2 this strip is located in a position immediately below spring strips 18 and 19 in alignment with the juncture of the astragalus 3 and the scaphoid 5. By locating the transverse strip 22 in this vital position I have found that very substantial comfort is imparted to the foot and fatigue is appreciably lessened. The transverse strip 22 forms a cantilever spring support at 23 and extends beneath the superimposed spring strips 18 and 19. Sufficient yieldability is possessed by spring strip 22 to allow spring strips 18 and 19 to yield upwardly and downwardly, and yet a sufficient limitation or restraint is imparted to the yieldability of strips 18 and 19 to maintain proper support for the bones of the foot in the vital positions requiring support. The transverse strip 22 passes over the recess provided at 14 in plate portion 12 and is further supported by the ledge at 12a coextensive with plate portion 12. The

calcaneus supporting portion 16 is provided with apertures 24 through which connections are made to the shoe.

In Fig. 9 I have illustrated the application of the principle of my invention to an arch support for use in women's shoes, wherein the arch support is elongated in contour as represented at 25 having an unsymmetrical metatarsal supporting portion 26 extending from the end of one side thereof and the substantially symmetrical calcaneus supporting portion 27 extending from the opposite end of the same side thereof. The calcaneous supporting portion 27 is slotted at the end thereof as represented at 27a to facilitate the securing of the arch support over the heel of a women's shoe. In this construction the spring members corresponding to springs 18 and 19 heretofore described are represented at 28 and are curved outwardly as represented at 28a before reaching the point of support in order to meet the requirements encountered in relatively narrow shoes. The same type of slidable connection is provided for the end spring strips 28 with the metatarsal supporting portion 26, at 29, and with the calcaneus supporting portion 27, at 30. The arch support is strengthened by a longitudinally extending rib 31 in the plate portion 25. The transversely disposed resilient lever member 32 extends under the sets of springs 28 and is connected at 33 with the plate portion 25 and functions in a manner similar to the spring strip 22 described in connection with Figs. 1-8.

Figs. 10-13 more clearly illustrate the application of the arch support of my invention to a welt-type shoe. I have indicated the shoe as having insole 9 sewed to the upper 34 and stitched to the welt 35 which connects to the outersole 10. The arch support is of such width that it fits between the stitched edges of the insole 9, upper 34 and welt 35 when secured in position by fastening means 23 driven into heel 36. The arch support clears the edges of the insole 9, the upper 34 and the welt 35 sufficiently to allow springs 18 and 19 to yield without obstruction in the edges of the insole, the upper or the welt. The transversely extending yieldable lever 22 is also free to move to allow sustaining the springs 18 and 19. A yieldable filling of selected material, such as cork, felt, or synthetic material 37, is provided as a cushioning means for the arch support between the arch support and the outersole 10.

There are constructions of shoes which require sewing operations so close to the longitudinal springs 18 and 19 of the arch that sometimes it becomes desirable to provide for the mounting of the springs 18 and 19 closer to the longitudinal axis of the shoe, as shown more particularly in Figs. 14-17. To provide for such contingencies I may form the original sheet metal punching with spaced rivet holes at 38 and 39 in the metatarsal supporting area 15a, and 40 and 41 in the calcaneus supporting area 16a. Where springs 18 and 19 are too close to the welt of the shoe in certain types of shoes to permit a proper sewing operation with the spring strips 18 and 19 supported by rivets 20 and 21 passing through apertures 39 and 41 in the arch support, the strips 18 and 19 can be moved inwardly and supported by rivets 20 and 21 passing through apertures 38 and 40 in the arch support, as shown more clearly in Figs. 14 and 15. The laterally extending spring strip member 22 is arranged in a manner similar to the structure heretofore de-

scribed where rivet 23, fastening strip 22, fastens to rivet aperture 42 in the plate portion 12 of the arch support.

There are occasions where the semi-rigid plate 12 of the arch support and the metatarsal supporting portion 15 which connects therewith may be further reinforced or strengthened. This may be accomplished as illustrated in Fig. 18 by curving the downstruck rib 14 into a path which continues into the metatarsal supporting portion 15 as represented at 43. In this way, both a lateral and a longitudinal reinforcement is applied to the metatarsal supporting portion 15 and to the intermediate portion of plate 12 which connects with metatarsal supporting portion 15.

I have illustrated in Figs. 19-29 the application of a metatarsal supporting member 44 added to the metatarsal supporting portion 15 of the arch support of my invention. The metatarsal supporting portion 44 is shown more clearly in Figs. 24-29 from which it will be observed that the support is cardioid-shaped and is pressed upwardly to provide a vertically projecting support for the metatarsal portion of the foot. The cardioid-shaped metatarsal supporting portion 44 has a maximum altitude at substantially the center of the metatarsal 7 from which it gradually tapers to the flat peripheral edge thereof of substantially cardioid-shaped contour represented at 44a in Fig. 25 and which rests directly upon the metatarsal supporting portion 15 of the arch support, as represented more clearly in Fig. 20. The metatarsal support 44 is shell-like and has a hollow interior providing a lightweight dome-like support for the foot in the metatarsal area thereof. The substantially cardioid-shaped metatarsal supporting portion 44 terminates in an integrally connected lug 45 formed adjacent the front thereof which carries an aperture 46 therein through which rivet 47 passes for securing the metatarsal support 44 to the metatarsal supporting portion 15 of the arch support. I have found this upwardly extending metatarsal support very effective in connection with the yieldable structure of the arch support shown in Figs. 19-23 and heretofore explained in detail.

In Figs. 30 and 31 I have shown a further modified form of arch support embodying my invention wherein a pair of spring strip members 48 and 49 are arranged in superimposed relation, but their rear ends are pierced merely by rivet holes and not by a slot comparable to the slots 18b and 19b in connection with the longitudinally extending springs 18 and 19 heretofore described. These rivet holes in resilient strips 48 and 49 have a rivet 50 extending therethrough and fastened to the supporting area 16a of the calcaneus supporting portion 16. These rear ends of strips 48 and 49 are anchored and are not free to slide. However, the forward end of strips 48 and 49 are provided with slots 48a and 49a and provide for the passage of a rivet 51 in the supporting area 15a of the metatarsal supporting portion 15. Strips 48 and 49 are yieldable over the pressure of the foot during walking and with the ends fixed at 50 variably slide within limits fixed by slots 48a and 49a in the forward ends of the strips to which rivet 51 extends. The transverse spring strip 22 supports the spring strips 48 and 49 at the juncture of the astragalus 3 and the scaphoid 5 as heretofore explained in connection with the other forms of the arch supports of my invention.

I have found the structure as set forth herein

highly practical and successful in operation, and while I have described my invention in certain preferred embodiments I realize that modifications may be made and I desire that it be understood that no limitations upon my invention are intended other than may be imposed by the scope of the appended claims.

What I claim as new and desire to secure by Letters Patent of the United States is as follows:

- 10 1. A device of the class described comprising a metallic strip having an enlarged portion projecting at one side of each end thereof leaving a gap therebetween and spring strip members extending longitudinally across said enlarged portions, and means supporting said spring strip members intermediate the ends thereof supported by said metallic strip.
- 15 2. A device of the class described comprising a metallic strip having an enlarged portion projecting at one side of each end thereof leaving a gap therebetween and spring strip members extending longitudinally across said enlarged portions, and a spring strip member projecting laterally from said metallic strip to a position beneath said spring strip members intermediate the end supports thereof.
- 20 3. A device of the class described comprising a metallic strip having an enlarged portion projecting at one side of each end thereof leaving a gap therebetween and spring strip members extending longitudinally across said enlarged portions, and a transversely arranged spring strip connected with said metallic strip and constituting a support for said spring strip members intermediate the end supports thereof.
- 25 4. An arch support comprising an elongated metallic member having a heel supporting portion projecting from the side of one end thereof and a sole supporting portion projecting from the same side of the other end thereof, a spring member supported between the said side projecting portions and a transversely extending member connected with said elongated metallic member and extending beneath and supporting said spring member.
- 30 5. A device of the class described comprising a metallic strip having an elongated metallic portion, an enlarged portion projecting at one side of each end thereof leaving a gap therebetween, a pair of flat spring strip members extending longitudinally across said enlarged portions in alignment with the other side projecting portion, and a transverse spring member extending substantially normal to the aforesaid flat spring members and extending therebetween, and fastening means for securing said transverse spring member to said elongated metallic portion.
- 35 6. In a device of the class described comprising a metallic strip having an enlarged portion projecting at one side of each end thereof and leaving a gap therebetween, a reinforcing rib extending longitudinally of said metallic strip and providing a flat ledge on each side thereof, a pair of spring strip members yieldably supported at opposite ends on the enlarged portions of said metallic strip and a transversely extending spring strip having its free end extending beneath said spring strip members, said transversely extending spring strip being secured to one ledge of said metallic strip and extending adjacent the other ledge of said strip across said reinforcing rib and supporting said spring strip members intermediate the ends supported by said metallic strip.
- 40 7. In a device of the class described comprising a metallic strip having an enlarged portion pro-

11

jecting at one side of each end thereof and leaving a gap therebetween, a reinforcing rib extending longitudinally of said metallic strip and providing a flat ledge on each side thereof, a pair of spring strip members yieldably supported at opposite ends on the enlarged portions of said metallic strip and a transversely extending spring strip having its free end extending beneath said spring strip members, said transversely extending spring strip being secured to one ledge of said metallic strip and extending adjacent the other ledge of said strip across said reinforcing rib and supporting said spring strip members intermediate the ends supported by said metallic strip, said spring strip members being confined with respect to said metallic strip and being free to slide at their opposite ends with respect to said metallic strip.

8. A device of the class described for facilitating the support of the foot comprising a metallic plate member having a calcaneus supporting portion projecting from the side of one end thereof and a metatarsal supporting portion projecting from the side of the other end thereof and in alignment with said calcaneus supporting portion, said metallic plate having a downstruck reinforcement rib therein extending between said calcaneus and metatarsal supporting portions, a pair of longitudinally extending spring members yieldably connected at opposite ends to said calcaneus and metatarsal supporting portions, and a transverse metallic strip connected with said plate intermediate said calcaneus and metatarsal supporting portions and projecting beneath said longitudinally extending members in a position

10

15

20

25

35

12

substantially between the astragalus and scaphoid bones of the foot for yieldably reinforcing said spring strips.

9. A device of the class described for facilitating the support of the foot comprising a metallic plate member having a calcaneus supporting portion projecting from the side of one end thereof and a metatarsal supporting portion projecting from the side of the other end thereof and in alignment with said calcaneus supporting portion, said metallic plate having a downstruck reinforcement rib therein extending between said calcaneus and metatarsal supporting portions, a pair of longitudinally extending spring members yieldably connected at opposite ends to said calcaneus and metatarsal supporting portions, and a transverse metallic strip connected with said plate intermediate said calcaneus and metatarsal supporting portions and projecting beneath said longitudinally extending members in a position substantially between the astragalus and scaphoid bones of the foot for yieldably reinforcing said spring strips, said reinforcement rib being curved from said plate into said metatarsal supporting portion.
